DESIGN FOR A TOY

Rida Payne Brashear, Castleton-on-Hudson, N. Y.

Application April 24, 1937, Serial No. 68,961

Term of patent 3½ years

To all whom it may concern:

Be it known that I, Rida Payne Brashear, a citizen of the United States, residing at Castleton-on-Hudson, county of Rensselaer, and State of New York, have invented a new, original, and ornamental Design for a Toy, of which the following is a specification, reference being had to the accompanying drawing forming a part thereof, in which—

Fig. 1 is a plan view of the toy showing my new design; and,

Fig. 2 is an elevational view thereof.

I claim:

The ornamental design for a toy as shown.

RIDA PAYNE BRASHEAR.
